DISPLAY DEVICE

Donald L. Primrose, Baltimore, Md.

Application August 19, 1933. Serial No. 685,949

12 Claims. (Cl. 46—49)

This invention relates to display devices, and in the form shown is also capable of use as a toy and for other purposes, and in the main it embodies a structure or structures taking advantage of the principle that like poles of magnets repel while unlike poles attract. In the embodiments of the invention shown in the accompanying drawings, one of the magnets is capable of reciprocating movement, while the other is provided with means whereby it (the second magnet) may be moved into or out of the magnetic field of the first magnet. Thus in combination with the action of gravity the first magnet is caused to reciprocate. In some forms of the invention the first or reciprocating magnet is concealed in a suitable body, such as that of the figure of a human being or a doll, while the second magnet is concealed in a suitable casing, and any suitable means are provided for moving the second magnet into and out of the magnetic field of the first magnet. There is thereby imparted to the body or figure in which the first magnet is concealed a reciprocating motion without means apparent to the observer for effecting such movement, and when placed on display in a show window, it is calculated to attract attention.

The inventive idea involved is capable of receiving a variety of mechanical expressions, some of which for the purpose of illustrating the invention are shown in the accompanying drawing, but it is to be expressly understood that such drawings are for the purpose of illustration only and are not designed to define the limitations of the invention, reference being had to the appended claims for this purpose.

In said drawing—

Fig. 1 is a vertical, longitudinal, medial section of a construction wherein a body with a magnet concealed therein is free to reciprocate in a vertical plane.

Fig. 2 is a vertical cross section on the line 2—2 of Fig. 1 looking in the direction of the arrows.

Fig. 3 is a vertical, longitudinal, medial section of a form of the invention wherein the reciprocable magnet is concealed in a cradle, and

Fig. 4 is a vertical, transverse section on the line 4—4 of Fig. 3, looking in the direction of the arrows.

Fig. 5 is a broken section of a structure corresponding to Fig. 1, showing a different body supported by the reciprocating magnet, and Fig. 6 is a modification.

Referring to the figures of the drawing in

which like reference numerals indicate like parts throughout the several views, and referring first to Fig. 1, 1 is a magnet concealed in and supported in a suitable body 3, which body 3 is here shown as having the general form or outline of a human figure, the said magnet and body being free to move vertically in suitable guideways 4—4, which guideways are preferably provided with upper and lower stops, the guideways being supported on standards 5—5, here shown as having the form of the head and foot of a bedstead. The standards 5—5 are supported in any suitable way, and as here shown they are carried by a casing 6, in which there is a disk 7 supporting the second magnet 8. Preferably there are a plurality of said magnets 8, here shown as four in number. The disk 7 is supported on a shaft 9, taking bearing in the end walls of the casing 6, and provided with any suitable means for imparting revolution thereto, said means being here shown in the form of a crank 10.

As here shown, the like poles of the magnets 1 and 8 are opposite each other and when the magnet 8 is brought within the magnetic field of the magnet 1, the effect is to repel the magnet 1 and cause it, with its supported body 3, to rise in the guideways 4—4, and when the magnet 8 passes out of the magnetic field, the magnet 1, with its supported body falls under the action of gravity. It will be manifest to those skilled in the art that if the magnet 8 were placed above the magnet 1 with the unlike poles opposite each other, the magnet 1 would be attracted toward the magnet 8 when the latter is brought within the magnetic field of the magnet 1 and when it passes out of said field, the magnet 1, with its supported body, would descend under the action of gravity, the principle of operation being the same as in the case shown in Fig. 1. By turning the crank 10 so as to bring the magnets 8, one after the other, into the magnetic field of the magnet 1, the latter with its supported body, can be caused to move up and down without any means visible to the observer for causing such movement, thus producing a mystifying effect calculated to attract the attention of the passer-by. Moreover, by giving the body 3 the form of a doll, a toy very attractive to children can be produced.

Preferably the standards 5—5 and the guideways 4—4 and the casing 6 are made of sheet metal which can be readily struck up at a minimum cost.

Referring now to Fig. 5, the construction is

identical with that of Fig. 4, except that in this case the body 3' takes the form of a girl supported by the magnet 1, and when the device is operated, the magnet 1 and the supported figure 3' will be caused to dance up and down.

Referring to Figs. 3 and 4, the casing 6, the disk 7, the magnet supported thereby, and the shaft 9 and crank 10 are identical with the construction shown in Fig. 1. Mounted upon the 10 casing 6 is a body in the form of a cradle 11, arranged to rock on the top of the casing 6, upon which casing are guide rails 12-12 to control the position of the cradle. Supported between the two end walls of the cradle 11 are two 15 magnets 1' and 1''.

Referring now to Fig. 4, when the magnet 8 is in the position shown in dotted lines to the left, and the disk 7 is being revolved clockwise, as indicated by the arrow, and with the like 20 poles of the magnets 1' and 8 opposite each other, the result will be that as soon as the magnet 8 is brought into the magnetic field of the magnet 1', the latter will be repelled, causing the cradle to rock to the right in Fig. 4, and 25 assume the right hand dotted position shown in said figure. This will move the magnet 1'' down into the position shown in dotted lines in Fig. 4, and as the magnet 8, under the continued revolutions of the disk 7, passes immediately under said magnet 1'', the latter will be repelled and the cradle rocked into the position shown by the dotted lines on the left hand side of said figure. With a plurality of magnets 8 another magnet 8 will immediately pass 30 under the magnet 1', and the operation will be repeated. Manifestly, instead of four magnets there could be one, two or three, or in fact there could be but one.

It will be perceived that in the two constructions shown in Figs. 1 to 4, both the reciprocal magnet and the magnet operating in conjunction therewith are concealed, and there is nothing exposed to the view of the observer that indicates what it is that produces the movements of 45 the body 3 or the cradle 11.

The construction in Fig. 6 is a modification of that shown in Figs. 1 and 2. Instead of having a series of magnets supported on a revolving disk as in Figs. 1 and 2, a plurality of magnets 50 8', 8' are mounted on rods 7', 7' within the casing 6, the rods being free to slide through openings in the wall of the casing to the end that magnets 8', 8' may be advanced under the magnet 1 and within the magnetic field thereof, as 55 shown in full lines in Fig. 6, but when withdrawn into the position shown in dotted lines in said figure, they are either entirely out of the magnetic field or are not sufficiently advanced within said field to exercise sufficient repulsion 60 to cause the magnet 1 and its supported body 3 to be elevated into the position shown in full lines in Fig. 6. For the purpose of holding the magnets 8', 8' in withdrawn position, any suitable spring construction may be employed. As 65 here shown, springs 7'', 7'' are connected one end to the casing 6 and one end to the magnet 8', 8', and when the magnets are advanced by pushing inward on the rods 7', 7', said springs are extended; when pressure is withdrawn from 70 said rods the springs withdraw the magnets 8', 8' into the position shown in dotted lines in Fig. 6.

Various modifications of the invention will readily suggest themselves to one skilled in the 75 art, and such modifications as fall within the

terms of the appended claims are intended to be covered thereby.

What is claimed is:

1. In a device of the character described, the combination of a magnet free to reciprocate, means for guiding said magnet in its reciprocation, a second magnet supported approximately parallel with said first magnet, and means alternately moving said second magnet into and out of the magnetic field of said first magnet. 80

2. In a device of the character described, the combination of a magnet free to reciprocate, means for guiding said magnet in its reciprocation, a second magnet supported approximately parallel with said first magnet, means alternately moving said second magnet into and out of the magnetic field of said first magnet, and means concealing said second magnet from view. 85

3. In a device of the character described, the combination of a magnet free to reciprocate, means for vertically guiding said magnet in its reciprocation, a second magnet supported approximately parallel with said first magnet, and means alternately moving said second magnet into and out of the magnetic field of said first magnet. 90

4. In a device of the character described, the combination of a reciprocable body, a magnet concealed in said body, means guiding said body in its reciprocations, a second magnet mounted 105 approximately parallel with said first magnet, and means alternately bringing said second magnet into and out of the magnetic field of said first magnet.

5. The combination of a reciprocable body, a 110 magnet concealed in said body, means guiding said body in its reciprocations, a second concealed magnet mounted approximately parallel with said first magnet, means concealing said second magnet from view, and means alternately 115 bringing said second magnet into and out of the magnetic field of said first magnet.

6. The combination of a reciprocable magnet, means for guiding said magnet in its reciprocations, a body supported by said magnet, a second 120 magnet supported for movement into and out of the magnetic field of said first magnet, and means for bringing said second magnet into and out of said magnetic field. 125

7. The combination of a magnet mounted to 125 reciprocate in a vertical plane, a second magnet mounted substantially parallel to said first magnet, and means alternately moving said second magnet into and out of the magnetic field of 130 said first magnet, whereby said first magnet is moved in one direction by magnetic action and in the reverse direction by gravity.

8. The combination of a reciprocable magnet, means guiding said magnet in its reciprocations, a plurality of magnets mounted for movement serially into and out of the magnetic field of said reciprocable magnet, and means imparting such movement to said plurality of magnets. 135

9. The combination of a magnet mounted on a rocking support, a second magnet mounted for movement into and out of the magnetic field of said first named magnet, and means for imparting said movement to said second magnet. 140

10. The combination of a single reciprocable magnet, with a plurality of reciprocable magnets, means normally holding said plurality of magnets without the magnetic field of said first named magnet, and means for advancing 150

said plurality of magnets into said magnetic field.

11. The combination of a single reciprocal magnet, with a plurality of reciprocal magnets, means normally holding said reciprocal magnets without the magnetic field of said first named magnet, and means for advancing each of said plurality of magnets within the magnetic field of said first named magnet.

10

12. The combination of a single magnet mounted to have free reciprocation, a plurality of concealed magnets, springs normally holding said concealed magnets without the magnetic field of said first named magnet, and means advancing said plurality of magnets into said magnetic field against the tension of said spring.
